OSCAR EISENKRAMER, OF NEW YORK, N. Y.

SNAP-FASTENER BINDING.

1,146,696.

Specification of Letters Patent. Patented July 13, 1915.

Application filed December 30, 1914. Serial No. 879,654.

To all whom it may concern:

Be it known that I, OSCAR EISENKRAMER, a subject of the Emperor of Germany, and a resident of the city of New York, borough 5 of Manhattan, in the county and State of New York, have invented a new and Improved Snap-Fastener Binding, of which the following is a full, clear, and exact description.

10 My invention has reference to a closing device to be used mainly with undergarments, and serves simultaneously as a binder for the edges of the undergarment where the closing means are to be provided.

15 The object of the invention is to provide a simple, efficient, and inexpensive closing device which is in the form of a tape, carrying the closing means, ready to be attached to the edges of an undergarment where the 20 closing means are to be provided and whereby all the closing means are secured at once. The tape carrying the closing means, further, serves as a binder for the closing edges of the garment.

25 With the above and other objects in view, the nature of which will more fully appear as the description proceeds, the invention consists in the novel construction, combination and arrangement of parts as herein 30 fully described, illustrated and claimed.

In the accompanying drawings, forming part of the application, similar characters of reference indicate corresponding parts in all the views, and Figure 1 is a perspective 35 view of a fragment of a garment provided with an embodiment of my invention; Fig. 2 is a section on line 2—2, Fig. 1; Fig. 3 is an elevation on a strip carrying the studs; Fig. 4 is an elevation of a strip carrying the 40 sockets; Fig. 5 is a cross section through the strip and shown in Fig. 3; Fig. 6 is a section through the strip shown in Fig. 4.

Referring to the drawings, the tape carrying the fasteners consists of an elongated 45 member 9 of any suitable material, the longitudinal edges 10 of which member are folded toward each other so that a gap is left between the facing edges of the folded portions 11 of the elongated member. Passing through one of the folded portions 11 and through the contacting-therewith part of the elongated member 9 are snap-fastener parts 12 or 13, according to whether the elongated member 9 carries the sockets or 50 the studs. The fastener parts maintain the folded portions 11 against the part of the

elongated member 9 contacting therewith by means of flanges 14 forming part of the fastener members, said fastener members being spaced on an elongated member at proper 60 intervals. After securing the snap-fastener members 12 or 13 to the elongated member 9, the same is folded in its middle so as to bring the folded portions 11 against each other. The so-folded elongated member 9 65 may be of any length, from which strips of desired length may be cut off and secured to unfinished garment edges which are to be provided with closing means.

The unfinished edge 15 of the garment is 70 fitted between the folded strip as shown in Figs. 5 and 6, and the same can then be stitched to the garment along the fold 16 of the strip and also along the other fold formed by the portions 11, as shown at 17. 75 It is self-evident that the coöperating edges of the garment are provided with strips, one carrying the male fasteners and the other the female part thereof. A strip such as described will not only make a binder for the 80 edge of the garment, but simultaneously provide therefor closing means, which can be quickly detached from one another, due to the fact that the closing means are of the snap-fastener type. It will be further remarked that only the coöperating parts of the snap-fastener will lie outside of the binding strips 9; and when the garment is 85 closed the coöperating parts of the fasteners are engaged, and, consequently, no part 90 thereof, that is, no metal part, can touch the body. When the strips are to be used on garments already provided with bindings, the strips shown in Figs. 5 and 6 can be previously stitched at their sides, that is, at the 95 fold 16 and at the opening formed by the folded-in edges 11.

From the foregoing description, taken in connection with the accompanying drawings the advantage of the construction of 100 my snap-fastener binding will be readily understood by those skilled in the art to which the invention pertains; and I desire to have it understood that the snap-fastener binding shown is merely illustrative and 105 that such changes may be made as are within the scope of the appended claim.

Having thus described my invention, I claim as new and desire to obtain by Letters Patent:

In a snap-fastener binding, a strip of fabric folded longitudinally in the middle

thereof and having its longitudinal edges folded in so that the major part of each side of the folded strip is substantially double, and snap fasteners attached to said strip so that one part thereof passes through the doubled side of the folded strip and has a part thereof located between the folded strip.

In testimony whereof I have signed my name to this specification in the presence of 10 two subscribing witnesses.

OSCAR EISENKRAMER.
